UNITED STATES PATENT OFFICE.

JOHN F. POORE, OF WACO, TEXAS.

ALARM FOR INCUBATORS.

1,205,929.

Specification of Letters Patent. Patented Nov. 21 1916.

Application filed August 31, 1915. Serial No. 48,326.

To all whom it may concern:

Be it known that I, JOHN F. POORE, a citizen of the United States, residing at Waco, in the county of McLennan and State of Texas, have invented certain new and useful Improvements in Alarms for Incubators; and I do hereby declare the following to be a full, clear, and exact description of the invention, such as will enable others skilled in the art to which it appertains to make and use the same.

This invention relates to alarm attachments for incubators, and the primary object of the invention is to provide an electrically operated alarm, which is automatically operated upon the raising or lowering of the temperature within the incubator, for sounding an alarm.

Another object of this invention is to provide an electrical alarm mechanism which is carried by the incubator exteriorly thereof, by means of which access may be readily gained to the signaling mechanism for throwing it out of an operative position.

Another object of this invention is to provide an electrical signaling mechanism for attachment to incubators, which includes a switch contact operated by the raising or lowering of the temperature within the incubator, for closing a circuit between a pair of adjustable contacts and a signaling mechanism, and to adjustably support the circuit closing contacts for regulating the sounding of the signal at any desired thermal degree of heat within the incubator.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate the like or corresponding parts throughout the several views, and in which:—

Figure 1 is a side elevation of an incubator, showing the improved signaling mechanism attached thereto, Fig. 2 is a top plan view of a fragment of an incubator and the improved signaling attachment, Fig. 3 is an enlarged fragmentary end view of the signaling mechanism, Fig. 4 is an edge view of the adjustable contact, Fig. 5 is a side elevation of the adjustable contact, showing various adjustments thereof in dot-

ted lines, Fig. 6 is a detail perspective view of one of the adjustable contacts, and Fig. 7 is a detail perspective view of the other adjustable contact.

Referring more particularly to the drawings, 1 designates an incubator of any ordinary construction, which has a heater 2 secured to one end thereof, for the purpose of maintaining the desired temperature within the incubator for insuring the hatching of eggs. The heater 2 has communication with the interior of the incubator through a transversely extending pipe 3, which communicates with a vertical pipe 4, extending upwardly from the burner 5 of the heater.

The damper 6 is positioned upon the upper open end of the vertical tube 4, and it has a wire 7 connected thereto, which extends upwardly and has its upper end connected to an arm 8. The arm 8 is secured to the side of the incubator 1 in any suitable manner, as is indicated at 9 in Fig. 1 of the drawings. The wire 7 is connected to a bar 10, which bar is pivotally connected intermediate of its ends to the arm 8. The wire 7 is connected to one end of the bar 10, and a weight 11 is mounted upon the other end of the bar, to counterbalance the weight of the damper 6. The wire 7 extends upwardly through an eye 12, which is secured to the damper lever 13. The damper lever 13 is pivotally carried by a bracket 14, which is secured to the incubator 1, and it has balancing weights 15 and 16 mounted upon its ends. The damper arm or rod 13 is a thermostat which moves in response to changes in temperature of the air surrounding it. The damper lever 13 has an arm 18 secured thereto as is shown at 19 to which arm is connected an electrical conductor 19. The electrical conductor 19 is connected to a binding post 20, carried by the incubator 1, which binding post is also connected to one pole of a battery or series of batteries indicated at 21 in the drawings.

The arm 18 is constructed of electrical conducting material, and it extends transversely across the end of the incubator, having its outer end positioned intermediate electrical contacts 22 and 23. The contacts 22 and 23 are pivotally carried by arms 24 and 25 respectively. The arms 24 and 25 are detachably connected to a bar 26 by means of screws 27 and 28, so that the position of the

rods 24 and 25 with respect to the bar 26 may be varied, by the loosening of the screws. The bar 26 is pivotally connected to a bracket 29, which bracket is securely attached to the incubator 1. The contacts 22 and 23 are pivotally mounted upon the angled end of the rods 24 and 25, as is clearly shown in Fig. 2 of the drawings, and they are positioned in the path of the movement 10 of the arm 18, so that when the arm rises, it will engage the contact 22, and when it lowers, beyond its normal position, it will engage the contact 23. The contacts 22 and 23 have elongated sides 30 and 31 formed 15 thereupon, which form handles for manually moving the contacts upon their pivotal points. Plates of insulation 32, are secured to the contacts 22 and 23 and are positioned for engagement with the arm 18, when the 20 contacts are moved manually, upon their pivotal points, for cutting off a circuit through either one of the contacts and the arm 18. The contacts 22 and 23 are connected to a binding post 34, by means of an 25 electrical conducting wire 33, which wire is connected to the arm 26. The arm 26 and the rods 24 and 25 are formed of conducting material, so as to permit of the passage of an electrical current therethrough. The binding 30 post 34 is connected to an electrical signaling mechanism 36 by means of an electrical conducting wire 37. The opposite pole of the electrical signaling mechanism 36 is connected to one pole of the battery 21, 35 oppositely of the pole to which the binding post 20 is connected, so that when the arm 18 engages either of the contacts 22 or 23, a circuit will be closed through the arm 18, either of the contacts, the signaling mechanism 36, and the battery 21, for sounding an 40 alarm. The contacts 22 and 23 are substantially U-shaped, having legs 40 and 41, which are connected by a plate 42, forming a socket for receiving the ends of the arm 18. 45 The wire 7 is slidably mounted within the eye 12, and it has a stop 43 formed thereupon, for limiting the slideable movement of the wire within the eye, and for causing the rod 13 to move synchronously with the wire 50 and the damper 6, after the damper has moved a predetermined distance upwardly.

In the operation of the improved signaling or alarm mechanism for attachment to incubators the rod or arm 13 being a thermostat moves in response to changes in temperature of the air surrounding it, which temperature is dependent upon a circulation current of heated air which passes out of the incubator 1 through the tube 2, upwardly 55 through the lamp 4 and into the incubator again through the tube 3. The movement of the arm 13 will correspondingly raise or lower the damper 6 as the temperature about the arm is high or low and thus vary the activity of the heating element 4. In case the

regulation of the damper 6 is insufficient in keeping the temperature within certain limit, the alarm bell is set going to attract the attention of an attendant. The contacts 22 and 23 may be adjusted, for causing connection with the arm 18 at any desired thermal degree, by the adjusting of the rods 24 and 25 and the arm 26. The heat or temperature rising within the incubator will move the damper 6 upwardly, and also the thermostatically controlled rod 13, which will move the arm 18 upwardly. When the temperature reaches a certain thermal degree, the outer end of the arm 18 will engage the contact 22, or the angled end of the 70 rod 24, which will close a circuit through the battery 21 and the signaling mechanism 36, sounding an alarm, for acquainting a person of the rise of temperature within the incubator. The circuit is broken, between 75 the battery 21 and the signaling mechanism 36, by moving the contact 22 upon its pivotal connection or mounting upon the rod 24 and causing the insulating plate 32 carried thereby to engage the arm 18, as is shown in 80 Fig. 5 of the drawings. This will break the circuit, and stop the operation of the signaling device 36. The heater 2 may then be adjusted, as desired. When the temperature 85 lowers within the incubator, the damper 6, 90 and the rod 13 will move downwardly, moving the arm 18 out of engagement with the contact 22. Owing to the loose mounting of the contacts upon the angled end of the rod 24, and the weight of the extension 95 100 formed thereon, the contacts will automatically fall into the position indicated in Fig. 4 of the drawings, or in other words automatically fall into an operative position upon engagement by the arm 18. When the 105 temperature within the incubator reaches a low predetermined thermal degree, the end of the arm 18 will engage the contact 23, or the angled end of the rod 25, closing a circuit between this rod and contact and the 110 battery 21 and the signaling mechanism, which will sound an alarm for acquainting a person of the fact that the temperature within the incubator is too low. The circuit is broken through the signaling mechanism 115 36, by moving the contact 23 upon its pivotal mounting upon the angled end of the rod 25, so that the insulating plate 32 carried thereby will engage the end of the arm 18. When the heat rises within the incubator, 120 the arm 18 will move upwardly, and permit the contact 23 to automatically move into an operative position, by the weight of the extension 31 formed thereon. Under normal temperature within the incubator, the arm 125 18 will be held suspended between the contacts 22 and 23, as is clearly shown in Fig. 1 of the drawings.

From the foregoing description taken in connection with the accompanying drawings, 10

the advantages of construction and of the method of operation of the improved alarm for incubators will be readily apparent to those skilled in the art to which this invention appertains and, while in the foregoing description, the principle of the operation of this invention has been described together with various features of construction, it is to be understood that certain minor features of construction, combination and arrangement of parts may be altered to suit practical conditions provided such alterations are comprehended within the scope of what is claimed.

15. What is claimed is:—

1. In a circuit make and break mechanism, a thermostatically controlled electrical conductive arm, a pair of arms, contacts pivotally carried by said arms and normally held within an operative position for engagement with said thermostatically controlled arm, and insulating plates carried by said contacts.
2. In a circuit make and break mechanism, a thermostatically controlled electrical conductive arm, a pair of pivotally mounted contacts, said contacts being adjustable with respect to each other, insulating plates carried by said contacts, said contacts being movable for moving said insulating plates into engagement with said arms for breaking an electrical circuit.
3. In a circuit make and break mechanism, a thermostatically controlled arm, a pivotally supported arm, a pair of rods adjustably connected to said pivotally supported arm, a pair of contacts pivotally car-

ried by the outer ends of said rods, insulating plates secured to one side of said contacts, extensions formed upon said contacts for normally holding them in a position for electrical engagement with said thermostatically controlled arm, said contacts being pivotally supported for moving said insulating plates into engagement with said thermostatically controlled arm.

4. In a circuit make and break mechanism, a thermostatically controlled arm, a pivotally supported rod operatively connected to said arm for pivotal movement upon the rise or fall of the arm, an electrical conductive arm carried by said rod for synchronous movement therewith, a second pivotally supported arm, a pair of rods connected to the opposite ends of said last named arm for adjustable movement with respect to each other, a pair of contacts pivotally carried by the outer ends of said last named rods, said contacts being substantially U-shaped and having elongated extensions formed upon one side thereof for normally holding the contacts in a position for electrical engagement with said first mentioned arm, and insulating plates carried by said contacts for engagement with said first mentioned arm upon pivotal movement of the contacts.

In testimony whereof I affix my signature in presence of two witnesses.

JOHN F. POORE.
